UNITED STATES PATENT OFFICE.

HARVE P. THOMAS, OF SUMNER, IOWA.

DITCHING-MACHINE.

1,066,553.

Specification of Letters Patent.

Patented July 8, 1913.

Application filed February 15, 1913. Serial No. 748,543.

To all whom it may concern:

Be it known that I, HARVE P. THOMAS, a citizen of the United States, and residing at Sumner, in the county of Brewer and State 5 of Iowa, have invented certain new and useful Improvements in Ditching-Machines, of which the following is a specification.

This invention relates to certain new and useful improvements in ditching machines, 10 and relates more particularly to a machine adapted to the digging or providing of ditches for the laying of tiles, the primary object of the invention being to provide a machine for this purpose by means of which 15 such ditches may be easily and expeditiously made.

A further object of the invention is to provide in a machine of this character novel means for conveying the excavated earth out 20 of the ditch being dug and depositing the same out of the way of the path of the machine.

Another object is to provide in a machine of this character novel means for regulating 25 the depth of the ditch being dug as may be required or desired, and further to so mount and arrange the mechanism that the same may be adjusted relatively to the supporting truck as to permit of ready transportation of 30 the apparatus to different points.

With the above and other objects in view, the invention consists in the novel construction, combination and arrangement of parts as will be hereinafter more specifically 35 described and then claimed, reference being had in such description to the accompanying drawings illustrating an embodiment of my invention, without, however, confining myself to the embodiment shown, since various 40 changes may be made in the details of construction and arrangement of parts without departing from the general spirit of the invention, or the scope of the same as claimed.

In the drawings: Figure 1, is a view 45 partly in side elevation and partly in longitudinal section, of a ditching machine in accordance with my invention, the auger being shown lowered in position for operation, Fig. 2, is a top plan view of the machine, Fig. 3, is a detail view of the 50 cleaning mechanism for the dirt conveyer of the auger, and Fig. 4, is a detail view partly in side elevation, and partly in section, of a

modified form of dirt-conveying means for the auger.

A ditching machine, in accordance with my invention, embodies a supporting truck, an adjustable ditch-digging and dirt-conveying mechanism carried thereby, and a driving means for the dirt-digging and the 60 dirt-conveying means, together with means for causing the apparatus to travel forward along the line of the ditch to be dug. To this end, I provide a supporting truck, herein shown as comprising a four-wheeled type 65 of truck, embodying a frame and four supporting wheels. The front wheels 10, are mounted on the spindles of the front axle 11, while the rear wheels 12 are mounted upon the spindles of stub-axles 14, which are in 70 the nature of cranks, and have their support in the side-bars 15 of the supporting frame.

The supporting truck is adjustable both at its front and at its rear ends, the adjustments being independent of each other. I 75 do not desire to confine myself to any specific means for providing these adjustments, as obviously various well known means may be employed. For the purpose of illustration, I have shown the front adjustment as 80 consisting of an ordinary screw-adjustment designated generally as 16. Any other type of adjusting means may be readily substituted therefor, all that is required being a means for elevating or lowering the forward 85 end of the supporting truck, the lowering movement of course being limited by the front axle.

Near the front end of the supporting truck I provide a suitable mounting for an 90 explosive or other form of engine 17, herein shown as mounted on platform-boards 18 secured to cross-members 19 attached at their ends to the side bars 15 of the supporting frame. The rear member also acts as a 95 support for a bearing 20, which receives the shank of a hanger 21 having a forked or yoke-shaped lower end in which is mounted a pair of concave-disks 22 preferably set with their forward edges running close together and their rear edges more widely separated so as to cut away the sod and remove rubbish in the line of the ditch to be dug. The hanger is adjustable in its bearing 100 so as to vary the depth which the disks enter 105 the ground as desired, and is so mounted

also as to be moved out of the path of the auger when the latter is raised for transporting the device, as will more fully appear hereinafter. It will be obvious that 5 any preliminary trench-forming device may be substituted for the concave disks shown, without departing from the scope of the invention.

The ditch digging or forming mechanism 10 proper is in the nature of an earth-auger 23 disposed near the rear end of the truck, and at an oblique angle with respect to the side bars of the supporting frame. At its lower end, the shaft or stem of this auger is journaled in a shoe 24, and at its upper end is journaled in a cross-bar 25, which is provided at the upper forward ends of arms 26. At the ends of the cross-bar 25, the same is provided with bearings or sleeves 27 in 15 which is received the cross-shaft 28 that is mounted at its ends in the upper ends of inclined supporting bars 29, secured at their lower ends to the side-bars 15 of the supporting frame of the truck, and supported 25 at said upper ends by struts 30. The arms 26 are bowed rearwardly from their upper ends, and the lower portions of these arms sweep forwardly and downwardly, and the lower ends of the arms are connected, prefer- 30 ably with a pivotal-connection, with the shoe 24.

Rising from the arms 26 at their upper ends are standards or bearings 31, 31' in which are journaled short shafts 32, 32', 35 each of which carries on its inner end a pinion 33, and these pinions mesh with the bevel gear 34, carried on the upper end of the shaft or stem of the auger. The arms 26, also carry, at their upper portions, and 40 directly back of the bearings 31, 31', similar bearings 35, 35'; in these bearings is journaled a shaft 36 which extends beyond the bearing 35' and carries at its extended end a sprocket wheel 37, receiving a sprocket 45 chain 38 passing over said wheel, and over a similar sprocket wheel 39 on the outer end of shaft 32'. On the outer end of shaft 32, is a sprocket wheel 40, which receives a drive chain 41 passing thereover and over 50 a sprocket wheel 42 on the shaft of the engine 17.

The shaft 36, together with a shaft 43, journaled in bearings 44 carried by the shoe 24 constitute the carrier for an endless conveyor 45, which carries the excavated earth up to the top of the machine where it discharges same into a suitably supported chute or carry off 46 which is preferably of a form which will enable the discharging of the 55 earth out to one side or the other of the machine, and thus out of the way. This chute or carry-off I have shown largely diagrammatically, since it may be of any desired form as may be found most convenient or 60 desirable.

The conveyer belt, I prefer to provide with blades 45' as shown, which constitute the buckets of such conveyer, as I have found such construction admirably answers the purpose for which it was designed, since 70 each blade is required to carry but a relatively small amount of earth, and by utilizing blades, I am enabled to effectually clean the conveyer as the same reaches the point of discharge. This I accomplish by mounting 75 in the bearings 35, above the shaft 36, a shaft 46', which carries blades or vanes 47 that enter the space between the blades 45' as the latter pass over shaft 36, and thus effectually dislodge the dirt and discharge same into the chute or carry-off 46. The manner in which the blades 47 are engaged by the blades 45' and the blades 47 thereby brought into cleaning action will be best understood by consideration of Fig. 85 3, of the drawings.

The purpose of providing the crank-axles 14 for the rear wheels is to enable an adjustment of the rear portion of the supporting-frame, and thus regulate the depth of 90 ditch as desired. This I accomplish by providing pulleys 48 on the axles 14, outside the side-bars 15. Cables 49 have their rear ends connected to these pulleys, and their forward ends connected to pulleys 50 carried on the ends of a shaft 51, journaled in bearings 52, 52', carried by the side-bars 15. The bearing 52, carries a segmental-rack 53, one or the other of the notches in which receives a spring-pressed dog carried by the 100 adjusting lever 54, that is connected to the shaft 51. As will be obvious, with this construction, the movement of the lever 54 toward the forward end of the truck will cause the cables 49 to pull on crank-axles 14 so 105 as to bodily elevate the rear of the supporting truck frame and the auger and conveyer mechanism. The strain upon the shoe 24 and the auger is relieved and transferred to the supporting truck by angular or offset 110 braces 55, attached at their lower ends to the arms 26, and at their upper ends to the side-bars 15, as at 56. The connection at 56 is, in practice, a readily separable one, such as a bolt, and the side rails 15 are 115 provided with one or more supplemental openings 57, and the braces 55 with one or more supplemental openings 58, so that when the auger and conveyer are swung in the supporting frame so as to elevate the shoe 120 above the ground level for transportation purposes, the bolt may be passed through openings 57, and 58, and thus utilize the braces 55 as the means for holding the shoe 125 in said elevated position. The bars 15 are connected at the rear end of the frame by a cross-bar 59 readily removable so as to allow of the swinging movement of the parts to bring the shoe to elevated position.

In order to begin work, the machine is 130

transported to the line where the ditch or trench is to be dug, and a short stretch of ditch is manually dug, sufficient to drop the auger to digging position, the same is adjusted to dig the desired depth, and the machine is then ready for operation. The machine is propelled forward along the line of the ditch being dug by means of a cable 60, attached at one end to a drum or reel 61 on the engine shaft, and at its other end to the forward end of the truck, or to the draft tongue, being passed around a tackle block as 62, securely anchored at a desired distance in front of the machine, thus imparting a forward motion to the whole machine when the engine is operated. While the machine is being thus propelled forward, the engine also drives chain or belt 41, and through shaft 32, spur gear 35, and gear 34 revolves the auger 23. The rotation of gear 34, causes motion to be imparted to shaft 32' through the meshing of pinion 33 with gear 34 and by means of chain or belt connection 38 with shaft 36, drives the conveyor 45.

Under some conditions, it is possible to dispense with the conveyor, since some kinds of soil will be carried up by the auger itself, and be discharged into the chute or conveyor off at the upper end thereof. On the other hand, in still other kinds of soil, it is sometimes desired to substitute for the endless conveyor above described, a semi-circular trough 63, as shown in Fig. 4 which is fixed up close to and underneath the auger 23 so that the auger will carry the loosened earth upward and discharge same into the spout or discharge chute 46.

When the machine is to be transported, bolts 56 are removed, and with connection 41 thrown off, the mechanism is thrown rearwardly, so as to elevate the lower end of the auger and shoe, the colter 22 being either raised or swung out of the way, and bar 59 removed so as not to interfere with the swinging of the parts. The bolts 56 are then engaged in apertures 57, and 58, so as to hold the lower end of the auger and the shoe in this elevated position so that the machine may be transported from place to place. The frame carrying the auger and mechanism may also be thrown backward for transportation, to permit which it may be necessary to dig under the shoe sufficient to give it clearance.

Having fully described my invention, what I claim as new, and desire to secure by Letters Patent is:—

1. In a ditch digging machine, a wheeled supporting truck, a shoe suspended beneath the truck in line with the center thereof, an auger journaled at its lower end in said shoe, a cross-shaft supported above the frame of the supporting truck, and a pair of arms sleeved at their upper ends onto said shaft

and at their lower ends connected to said shoe for supporting the latter and the auger.

2. In a ditch digging machine, a wheeled supporting truck, a shoe suspended beneath the truck, an auger journaled at its lower end in said shoe, a cross shaft supported above the truck, supporting arms sleeved at their upper ends onto the cross shaft and at their lower ends connected to the shoe for supporting the latter and the auger, and a conveyor disposed to carry off the earth loosened by the auger.

3. In a ditch digging machine, a wheeled supporting truck, independent adjusting means for each end of the truck, a cross shaft supported above the frame of the supporting truck, rearwardly bowed arms sleeved at their upper ends on to said cross shaft, a connecting bar between the arms at their upper ends whereby the arms are caused to swing in unison on the cross-shaft, a shoe to which the lower ends of the arms are connected, an auger disposed at an incline in the center line of the truck and journaled at its ends in said shoe and connecting bar respectively, driving means for the auger, a conveyor disposed to receive the earth from said auger, said conveyor carried by the arms and the shoe, and adjustable connections between the arms and the truck for providing different inclinations to the auger and conveyor.

4. In a ditch digging machine, a wheeled supporting truck, a cross-shaft supported above the frame of said truck, a pair of rearwardly-bowed arms sleeved at their upper ends to said shaft, a cross-bar connecting said arms at their upper ends, a shoe to which the lower ends of said arms are connected, an auger journaled at its lower end in said shoe and at its upper end in said cross-bar, a conveyor disposed to carry off the earth loosened by said auger, and driving means for the auger.

5. In a ditch digging machine, a wheeled supporting truck, a cross-shaft supported above the frame of said truck, a pair of rearwardly bowed arms connected at their upper ends and at said ends sleeved onto the cross-shaft, a shoe to which the lower ends of said arms are connected, an auger journaled at its lower end in said shoe and at its upper end in the connecting member of said arms, and means connecting the arms with the frame of the truck, said means adjustable to provide different inclinations to the auger.

6. In a ditch digging machine, a wheeled supporting truck, supporting-bars carried by the frame of said truck, a cross-shaft mounted in said supporting-bars, arms sleeved at their upper ends onto said cross-shaft, a connecting member between the upper ends of said arms, a shoe to which the lower ends of said arms are pivotally-con-

nected, an auger journaled at its ends in
said shoe and connecting member respectively,
a conveyer disposed to receive the
earth from said auger, and adjustable
connections between the arms and the supporting
truck permitting adjusting the auger to
different inclinations.

In testimony whereof I affix my signature
in presence of two witnesses.

HARVE P. THOMAS.
